UNITED STATES PATENT OFFICE.

FRED H. WHEELER AND CHARLES R. HOLCOMB, OF CHICAGO, ILLINOIS.

LEGGING.

1,220,806.

Specification of Letters Patent. Patented Mar. 27, 1917.

Application filed October 2, 1916. Serial No. 123,208.

To all whom it may concern:

Be it known that we, FRED H. WHEELER and CHARLES R. HOLCOMB, both citizens of the United States, residing at Chicago, in 5 the county of Cook and State of Illinois, have invented a certain new and useful Improvement in Leggings, of which the following is a specification.

Our invention relates to an improved legging for the use of molders for protecting the lower part of the leg from molten iron or for use by others engaged in occupations making it desirable to protect the lower part of the leg and the lower part of the trousers 15 from the burning or corrosive action of materials which are being handled by the workmen with the possibility of the burning or corrosive materials coming in contact with the lower part of the leg.

Our invention more specifically consists 20 of a legging constructed from fabric or leather treated with fire-proofing compound or not, as desired, and supported by a metallic framework of novel construction as 25 will appear more clearly from the detailed description of the drawings below, which present one embodiment of our invention.

Our improved legging is quickly applied 20 to the leg of the user and may be instantly removed therefrom if desired and affords complete protection against the action of burning or corrosive materials which may be spilled or come in contact with the legging.

Our invention will be more clearly understood 25 from the accompanying drawings, presenting one embodiment thereof, in which—

Figure 1 shows in a perspective view the 40 complete legging, and

Fig. 2 shows in developed inside view the legging construction shown in Fig. 1 with the lower foot protecting portion removed.

Similar numerals refer to similar parts 45 throughout the several views.

As shown in the drawings, the legging consists of a sheet of leather or fabric 1 provided with a plurality of reinforcing strips of metal, indicated generically by 2 in Fig. 1, which extend both longitudinally 50 and laterally of the legging. At the lower portion of the sheet of material 1 a foot protecting portion or flare 3 is secured, shaped to cover the upper part of the shoe of the user, this flare being constructed either of 55 fabric or leather, as desired, and fastened

to the lower end of the sheet of material 1 by rivets or stitching as preferred. The metal reinforcing strips are more clearly shown in Fig. 2 at 6, 7, 8, 9, 13, 14 and 15. 60 The strips 6, 7, 8, 9 and 13 extend longitudinally of the legging and of these strips the strips 6, 7, 8 and 9 are preferably contained in pockets formed by hemming the left hand edge of the sheet of material 1 and sewing 65 strips of fabric or similar material 10, 11 and 12 to the inside of the sheet of material 1 as indicated in Fig. 2. It will be observed that the rows of stitching indicated along the edges of the strips 10, 11 and 12 terminate below the strip of metal 15 and above the strip of metal 14 and that the strips of fabric or other material 10, 11 and 12 are sewed, as indicated by the heavy dotted lines, at their ends to the sheet of material 70 1, the stitching at the upper ends of the strips 10, 11 and 12 being put in place after the strips of metal 7, 8 and 9 have been inserted. As a result of the stitching described the strips of material 10, 11 and 12 75 form loops through which the reinforcing strips or bands 14 and 15 may be inserted.

The bands 14 and 15 are preferably of spring material and circular in form or nearly so, and after the stitching referred 80 to above has been completed these spring bands 14 and 15 are threaded through the loops at the points marked *a* and the ends of these spring bands are secured to the longitudinal stiffening members 6 and 13 by 85 rivets, as indicated, which extend through the sheet of material 1. Additional rivets may be inserted through the stiffening members 6 and 13 and the sheet of material 1 if 90 desired, as indicated.

It will be noted that the vertical stiffening members 6 and 13 extend below the lower edge of the sheet of material 1 and are provided with holes for receiving rivets as indicated in Fig. 1 for securing to these stiffeners the rear edges of the flaring portion 3 of the legging which may be secured to the lower edge of the sheet of material 1 by stitching or rivets, as desired. The right hand edge of the sheet of material 1, as indicated in Fig. 2, is extended beyond the longitudinal stiffening member 13 to form a flap 5 which, when the legging is placed upon the leg of the user, is placed around the leg inside of the stiffening member 6 105 110 which holds it in position through the action of the spring members 14 and 15. As a

result of this construction the legging may be put in place quickly and easily and if a considerable quantity of molten metal or acid, as the case may be, should strike the legging, the latter can be removed instantly from the leg of the user so as to eliminate all danger that might result from the legging being burnt through by the molten metal or acid.

10 As indicated in Fig. 1, the upper edge of the sheet of material 1, which projects some distance above the upper spring stiffener 14, is preferably taken in by means of a number of plaits 4, so that the upper edge 15 of the legging when in use presses closely against the trouser of the user so as to prevent acid or molten metal from passing downward inside of the upper end of the legging between the legging and the trouser leg of the user. To further provide a tight closure between the upper edge of the legging and the trouser leg underneath it, a drawstring 16 may be employed, if desired, by which the upper edge of the legging may 20 be securely tied in place which, under some conditions, is desired particularly if there is small prospect of being obliged to unexpectedly and quickly remove the legging.

While it is desirable to employ the pockets 30 10, 11 and 12 for receiving the longitudinal stiffeners 7, 8 and 9 respectively, these pockets may be omitted if a less finished legging is satisfactory, and rivets may be employed at the points indicated by the 35 letter *a* to hold the stiffening members in position upon the sheet of material 1.

We are aware that protective leggings have heretofore been constructed in different forms, some of which contemplate the 40 use of metal stiffening members, but as far as we are aware, we are the first to produce a legging of this kind in which the stiffening members are secured to the sheet of protective material by a pocket construction as described, and as far as we are aware, we are also the first to produce a legging of the 45 kind referred to in which the upper edge is formed to tightly engage the trouser leg of the user, so that molten metal or acid cannot flow downward between the legging and the trouser leg and, furthermore, we believe our construction to be novel in providing 50 longitudinal stiffening members which are extended downwardly to reinforce a flaring foot protecting portion to hold the latter in its proper shape.

We do not, therefore, limit ourselves to the exact construction shown in the drawings, but desire to cover by the appended 60 claims all equivalents thereof known to the art at the time of the filing of this application.

What we claim is:

1. In a legging, the combination of a sheet 65 of flexible protective material, flexible strips

secured to said sheet of material forming in connection therewith pockets extending longitudinally of the legging, metal stiffening members contained in said pockets, said strips of flexible material being secured at 70 their ends to said sheet of protective material and separate from said sheet of material intermediate of their ends forming loops adjacent the ends of the metal stiffening members, spring reinforcing members 75 extending circumferentially of the legging through said loops, and longitudinal metal stiffeners secured to the ends of said spring reinforcing members and to said sheet of material. 80

2. In a legging, the combination of a sheet of flexible protective material, flexible strips secured to said sheet of material forming in connection therewith pockets extending longitudinally of the legging, metal stiffening 85 members contained in said pockets, said strips of flexible material being secured at their ends to said sheet of protective material and separate from said sheet of material intermediate of their ends forming 90 loops adjacent the ends of the metal stiffening members, spring reinforcing members extending circumferentially of the legging through said loops, longitudinal metal stiffeners secured to the ends of said spring reinforcing members and to said sheet of material, said last named longitudinal stiffening members extending beyond the lower edge of said sheet of material, and a flaring shoe protecting portion secured to the projecting ends of said stiffening members and to the lower edge of said sheet of protective material. 100

3. In a legging, the combination of a sheet of flexible protective material, flexible strips 105 secured to said sheet of material forming in connection therewith pockets extending longitudinally of the legging, metal stiffening members contained in said pockets, said strips of flexible material being secured at 110 their ends to said sheet of protective material and separate from said sheet of material intermediate of their ends forming loops adjacent the ends of the metal stiffening members, spring reinforcing members 115 extending circumferentially of the legging through said loops, and longitudinal metal stiffeners secured to the ends of said spring reinforcing members and said sheet of material, said sheet of protective material being extended laterally beyond the longitudinal stiffening member connected with one end of the spring reinforcing members to form a flap held in place on the leg of the user by the longitudinal stiffening member 120 at the opposite edge of the legging. 125

4. In a legging, the combination of a sheet of flexible protective material, flexible strips secured to said sheet of material forming in connection therewith pockets extending 130

sheet of protective material extending without metal reinforcement above the upper spring reinforcing member and being taken in around its upper edge to closely fit the leg of the user.

9. In a legging, the combination of a sheet of flexible protective material, flexible strips secured to said sheet of material forming in connection therewith pockets extending longitudinally of the legging, metal stiffening members contained in said pockets, said strips of flexible material being secured at their ends to said sheet of protective material and separate from said sheet of material intermediate of their ends forming loops adjacent the ends of the metal stiffening members, spring reinforcing members extending circumferentially of the legging through said loops, longitudinal metal stiffeners secured to the ends of said spring reinforcing members and to said sheet of material, said sheet of protective material extending without metal reinforcement above the upper spring reinforcing member, and a draw-string extending through the upper edge of said sheet of protective material for securely fastening said upper edge around the leg of the user.

10. In a legging, the combination of a sheet of flexible protective material, flexible strips secured to said sheet of material forming in connection therewith pockets extending longitudinally of the legging, metal stiffening members contained in said pockets, said strips of flexible material being secured at their ends to said sheet of protective material and separate from said sheet of material intermediate of their ends forming loops adjacent the ends of the metal stiffening members, spring reinforcing members extending circumferentially of the legging through said loops, longitudinal metal stiffeners secured to the ends of said spring reinforcing members and to said sheet of material, said sheet of protective material being extended laterally beyond the longitudinal stiffening member connected with one end of the spring reinforcing members to form a flap held in place on the leg of the user by the longitudinal stiffening member at the opposite edge of the legging, said sheet of protective material extending without metal reinforcement above the upper spring reinforcing member, and a draw-string extending through the upper edge of said sheet of protective material for securely fastening said upper edge around the leg of the user.

11. In a legging, the combination of a sheet of flexible protective material, a plurality of longitudinal metal stiffening members, upper and lower spring reinforcing members extending laterally of said sheet and substantially circular in form, and devices connecting said reinforcing members together and to said sheet of material, said sheet of material extending above said upper spring reinforcing member without metal reinforcement and being taken in at its upper edge to closely fit the leg of the user.

12. In a legging, the combination of a sheet of flexible protective material, a plurality of longitudinal metal stiffening members the outer ones of which are connected with said sheet of material, and upper and lower spring reinforcing members extending laterally of said sheet to encircle the leg of the user and connected with said sheet of material, said sheet of material extending laterally beyond one of the outer stiffening members to form a flap held in place on the leg of the user by the other one of said outer stiffening members.

13. In a legging, the combination of a sheet of flexible protective material, a plurality of longitudinal metal stiffening members, upper and lower spring reinforcing members extending laterally of said sheet and substantially circular in form, devices connecting said reinforcing members together and to said sheet of material, said sheet of material extending above said upper spring reinforcing member without metal reinforcement, and a draw-string extending through the upper edge of said sheet of protective material for securely fastening the same to the leg of the user.

14. In a legging, the combination of a sheet of flexible protective material, a plurality of longitudinal metal stiffening members the outer ones of which are connected with said sheet of material, upper and lower spring reinforcing members extending laterally of said sheet to encircle the leg of the user and connected with said sheet of material, and a flaring shoe protecting portion secured to the lower edge of said sheet of material, the outer ones of said stiffening members being extended below said sheet of material and secured to said flaring portion.

In witness whereof, we hereunto subscribe our names this 28th day of September, A. D. 1916.

FRED H. WHEELER.
CHARLES R. HOLCOMB.
